UNITED STATES PATENT OFFICE.

EDGAR H. FREEMAN, OF TRENTON, NEW JERSEY.

INSULATING-LINING FOR ELECTRICAL LAMP-SOCKETS.

1,020,036.

Specification of Letters Patent. Patented Mar. 12, 1912.

Application filed June 21, 1911. Serial No. 634,593.

To all whom it may concern:

Be it known that I, EDGAR H. FREEMAN, a citizen of the United States, residing at Trenton, in the county of Mercer and State 5 of New Jersey, have invented certain new and useful Improvements in Insulating-Linings for Electrical Lamp-Sockets, of which the following is a specification.

This invention relates to the subject of 10 casings for electrical lamp sockets, and has particularly in view an improved means for fitting the cap of the socket casing with a permanent insulating lining that will effectually and satisfactorily fulfil all of the 15 requirements of the National Board of Fire Underwriters.

Heretofore various expedients have been resorted to for the purpose of securing in 20 place what is known as the cap lining for lamp sockets, which expedients have involved fastening projections or elements of 25 various kinds formed integrally or otherwise with the sheet metal cap, or with the shell part of the casing. In some forms of lining fastenings the resiliency of the insulating lining has been depended upon to 30 effect a locking action, while in other forms of construction effort has been made to permanently secure a rigid lining in place by suitable fastening elements.

In contradistinction to the known lining 35 fastening means above referred to, the present invention contemplates the provision of what may be termed a molded insulating lining for a socket cap, that is to say, the application to the cap of any suitable insulating material that is shaped to lining form while in a plastic state either within or without the cap, and then caused to become 40 set or hardened about and upon suitable anchoring projections within or upon the metal cap or the parts thereof. Any suitable insulating material capable of being handled in this way may be utilized in 45 carrying out the invention in this manner.

Though susceptible to a wide range of structural modification, the essential features of the invention are well exemplified in the accompanying drawings, in which—

50 Figure 1 is an enlarged sectional view of the casing cap of a lamp socket equipped with a molded insulating lining. Fig. 2 is an enlarged cross sectional view thereof on the line 2—2 of Fig. 1. Fig. 3 is an en-

larged sectional view illustrating a practical method of punching the inwardly projecting fractured anchor-spurs. 55

Like references designate corresponding parts in the several figures of the drawings.

Referring to the embodiment of the invention suggested in the drawings, the numeral 1 designates the cap part of a metallic casing or shell for an electrical lamp socket, of any conventional form or design, and designed to be lined upon its interior 60 with a lining or washer 2 of insulating material. This lining or washer when set to its final form, is of the dished type and of a size to register snugly within the correspondingly shaped cap. It is proposed to 65 permanently lock this lining in place. This may be accomplished in various ways but preferably by means of a plurality of inwardly projecting integral anchor spurs 3 which are forcibly punched inwardly from 70 the body material of the cap, by exterior means such as the pointed punches 4. The action of these punches is to fracture the spurs 3 so as to present ragged edges that 75 become embedded in the molded material while in a plastic state. Additional securing means may be provided by a dovetailed anchoring rib or ribs 5 provided within the crown of the cap, and which rib or ribs 80 likewise become embedded in the plastic material prior to its becoming set or hardened. 85

As indicated, any suitable insulating material may be employed to form the lining, 90 that is, any insulating material such as sulfur or rubber compositions that may be molded in plastic form and afterward allowed to become hardened in a final form. In this connection it may be observed that the cap itself may be utilized as the mold 95 for the plastic material to be painted, run, or pressed into place, or it is obvious that the lining may be separately molded in its proper form, then softened by heat and pressed into the cap over the anchors and 100 allowed to become set or hardened, and thus becoming a permanent part of the socket cap.

I claim:

1. As an improvement in electrical lamp 105 sockets, the combination of the socket casing having a sheet metal cap provided with introverted anchor elements, and a lining

of plastic insulating material permanently molded upon the inner surface of the cap and over said anchor elements.

2. As an improvement in electrical lamp 5 sockets, the combination of the socket casting having a sheet metal cap provided with introverted fractured prongs, and a lining of plastic insulating material permanently

molded upon the inner surface of the cap and over and about said prongs.

In testimony whereof I hereunto affix my signature in the presence of two witnesses.

EDGAR H. FREEMAN.
